UNITED STATES PATENT OFFICE.

THOMAS J. HISSEM, OF RICHMOND, INDIANA.

HARP.

SPECIFICATION forming part of Letters Patent No. 757,462, dated April 19, 1904.

Application filed October 19, 1903. Serial No. 177,584. (No model.)

To all whom it may concern:

Be it known that I, THOMAS J. HISSEM, a citizen of the United States, residing in the city of Richmond, in the county of Wayne, and in the State of Indiana, have made certain new and useful Improvements in Harps, of which the following is a specification, which when taken in connection with the accompanying drawings, forming a part thereof, is sufficiently clear and concise as to enable others skilled in the art to which it appertains to make and use the same.

My present invention does not contemplate a radical departure from the principles heretofore involved in the construction of harps, but rather the adoption of well-known principles with their mechanical elements reduced to their simplest proposition and the system and arrangement improved to accomplish the named objects and, as a natural sequence, accentuating the utilitarian and musical benefits thereof and adapting them to subserve the highest economic ends.

The object of my invention, broadly speaking, is to provide a harp composed of coöperating, interdependent, and subsidiary elements arranged and combined to subserve the highest economic ends and to produce the highest measure of efficiency.

Another object is the provision of a harp which will be comparatively easy of operation, compact in its several parts and proportions, to reduce the number of parts to a minimum without detriment to its musical efficacy, in which the parts are arranged and combined to cause the most direct response from the part to be acted on, in which the mechanical operations will be absolutely noiseless, and in which the construction will be symmetrical and pleasing to the eye in appearance.

A further object is to provide a harp adapted to be tuned eleven strings to the octave, thus enabling the performer to make a chromatic run with ease, and by means of my improvements the harp is rendered more efficient either for capricio, orchestral, operatic, or symphony work.

A still further object is to provide a harp having a positive, efficient, and easily-operated action for changing the tone of certain

of the strings thereof, each having independent mechanisms constructed to accomplish its object in the swiftest manner possible.

A further object is to provide a new system of arranging the strings of the harp in order that the gamut or scale may be run chromatically and also accomplishing the work with less manual labor and at the same time providing means whereby a higher grade of musical technique may be produced by the ordinarily proficient operator.

Other objects and advantages of my invention will appear from the following specification by reference to the accompanying drawings, and as more specifically pointed out in the accompanying claims.

The invention consists of the arrangements and combinations of the several parts, together with their configurations, substantially as shown in the accompanying drawings, in which—

Figure 1 is a side elevation of the upper portion of the left-hand side of my harp. Fig. 2 is a section of a portion of my harp, taken on the line X X of Fig. 1. Fig. 3 is a detail face view of one of the adjustable plates and disks and the means for operating same. Fig. 4 is a central section taken on the line Y Y of Fig. 3. Fig. 5 is a detail view of one of the bell-cranks. Fig. 6 is an isometrical view of one of the horizontal connecting-bars. Fig. 7 is a detail isometrical view of one of the spindles and its permanent arm secured thereto and the helical spring therefor. Fig. 8 is a detail view of one of the adjustable arms, and Fig. 9 is a detail view of one of the upwardly-extending connecting-bars.

Similar indices refer to and denote like parts throughout the several views of the drawings.

Referring now to my invention in detail, the numeral 1 denotes the head of my harp, 2 the body, 3 the neck, and 4 the column, which parts may be of any suitable form or construction, as desired. As is indicated in Figs. 1 and 2, a horizontal rectangular recess is cut out of the under side of the neck 3, extending from the post toward the rear of the harp, and an aperture corresponding thereto in cross-section is formed opposite thereto in the head 1, as indicated. The head 1 and the

column 4 are hollow, as suggested in the drawings. To the neck 3, on each side of said recess therein, is a plate—6 on the left and 6' on the right—secured by screws, as indicated in Fig. 5, 1, said plates being larger than said recess and mortised in, as shown, in order that their faces will be flush with the respective faces of the neck 3, as indicated in Fig. 2. By the above it will be manifest that a space is formed 10 in the neck by said plates.

Pivoted in the plates 6 and 6', across the space therebetween, are the spindles 8, 8^a, 8^b, 8^c, and 8^d, each having permanently secured thereto and extending up therefrom the 15 arms 10, 10^a, 10^b, 10^c, and 10^d. Extending across between said plates within the head 1 is a shaft 9, and pivoted thereon through the eyes 5^c are five bell-crank 5, 5', 5'', 5''', and 5'''', each having the eye 5^c for pivoting it to 20 the shaft 9, and also in the opposite points are the eyes 5^a and 5^b, as indicated in Fig. 5. The arms 10, 10^a, 10^b, 10^c, and 10^d are pivotally connected to the respective bell-crank 5, 5', 5'', 5''', and 5''''' by connecting-rods 12, 25 12^a, 12^b, 12^c, and 12^d, respectively. Pivoted in the eye 5^a of the bell-crank are connecting-rods *a*, *b*, *c*, *d*, and *e*, which extend down through the column 4, where each is connected 30 to a separate pedal for moving said rods *a*, *b*, *c*, *d*, and *e* endwise vertically and by which the rods 12, 12^a, 12^b, 12^c, and 12^d are thus adapted to be moved endwise horizontally.

Surrounding the spindles 8, 8^a, 8^b, and 8^c is a coil-spring 14, one end of which contacts 35 with the arm 10, 10^a, 10^b, and 10^c and the opposite end with the plate 6, and a similar spring 14 surrounds the spindle 8^d, one end of which contacts with the arm 10^d and the other end with the plate 6', the objects of said 40 springs 14 being to prevent the mechanism from rattling by keeping the adjustable outer arms contacted with their respective plates.

Adjustably secured by a set-screw to the left-hand ends of the spindles 8, 8^a, 8^b, and 8^c, outside the plate 6, are the respective arms 7, 7^a, 7^b, and 7^c, and adjustably secured by a set-screw to the right-hand end of the spindle 8^d, outside the plate 6', is the arm 7^d. The arms 8, 8^a, 8^b, 8^c, and 8^d have pivoted to 50 their outer ends the respective connecting-bars 13, 13^a, 13^b, 13^c, and 13^d, as shown.

The indices 15, 15^a, 15^b, 15^c, and 15^d each represent an identical adjustable plate, the four former being secured on the left-hand face of the neck 3 and the latter on the right-hand face of the neck 3 in the respective positions indicated in Fig. 1. Through each of said plates, near each side thereof, is a vertical slot 15' to receive each a screw A to be inserted in the side of the neck through said slots, whereby said plates may be adjusted vertically. In the center of the plate 15 is a threaded aperture to receive an axial screw B. Contacting with the plate 15 is the washer 16, 65 with a central opening therethrough through

which passes the screw B. Contacting with the washer 16 is the inner disk 17, also having a central opening through which passes the screw B and having two oppositely-disposed ears 17', extending out beyond its periphery, 70 with threaded screw-holes through said ears to receive the screws C and of same size as the disk 17, and contactable therewith is the outer disk 19, with a central opening therethrough to receive the screw B in such a manner that it will be flush with the face of the disk 19, as indicated. The heads of the screws C are adapted when tightened to engage the disk 19 and hold it securely in contact with the disk 17, or by loosening said screws the outer disk may be adjusted circumferentially, 75 as desired. Extending out from the face of two oppositely-disposed points near the outer edge of the disk 19 are the two fingers 20. Integral with the disk 17 and extending out 80 therefrom is the arm 18, having pivotally connected to its outer end the connecting-arm 13, above referred to. Immediately preceding I have referred more particularly to Figs. 3 and 4; but it should be understood that each of the 85 five disks and their individual mechanisms are of the same construction, and the above description of one particularly will answer for all.

I will now refer to two octaves of the strings 90 of my harp, it being understood that other similar octaves may be continued, as desired. Commencing nearest the column 4, the first eleven strings constitute the bass-octave, and the respective strings are designated by numbers and in musical terms, as follows: The numeral 50 denotes the F string; 51, the G string; 52, the A string; 53, the B-flat; 54, the B; 55, the C; 56, the C-sharp; 57, the D; 58, the E; 59, the F, and 60 the F-sharp. 95 Constituting the treble-octave the respective strings are designated by number and by musical terms, as follows: 61 denotes the G string; 62, the A string; 63, the B-flat; 64, the B; 65, the C; 66, the C-sharp; 67, the D; 68, the E; 69, the F; 70, the F-sharp, and 71 the G. The five disks I have shown are arranged to operate on the five strings 50, 51, and 57 in the bass-octave and 61 and 67 in the treble-octave, the disk 19 being located slightly back 100 of its respective string with the two fingers 20 thereof disposed one on each side of its string and being so arranged that by turning the disk 19 the fingers thereof will be caused to grasp its string, and when so brought into action the string operated on will be changed in tone to sharp—thus, for instance, the F string 50 may be changed to F-sharp, the G string 51 may be changed to G-sharp, the D string 57 may be changed to D-sharp, 105 the G string 61 may be changed to G-sharp, and the D string 67 may be changed to D-sharp—which operations are accomplished by depressing the respective rods *a*, *b*, *c*, *d*, and *e* by any suitable mechanical means, such as 110

pedals. In order to individualize each disk mechanism, they are to be known as follows: Beginning with the one nearest the head 1, the first is the F-sharp disk, the second is the 5 G-sharp disk, the third is the E-flat disk, the fourth is the G-sharp disk, and the fifth is the E-flat disk, and it will be apparent that by bringing the fingers of the disk into action with its string its string will be changed in 10 tone to that just indicated.

It will be obvious that, if desired, other connecting-arms, as 13' and 13", (shown in Fig. 1,) may be pivoted to the outer ends of the arm 18 in addition to the arms 13^c and 13^d 15 and extended to other disks to operate on correspondings strings in other corresponding octaves.

From the above it will also be apparent that the bass octave is complete in itself, 20 while the treble disks only are designed to be connected to other disks in order that, for instance, the G and D disks may be connected to other disks to operate on all G and D strings.

25 My harp is herein shown with thirty-five strings, while if constructed for operatic work I would prefer to have it equipped with fifty-five strings.

In actual practice I have found it preferable 30 to dispose the bass strings three-fourths of an inch apart, and the treble strings I dispose eleven-sixteenths of an inch apart, thus causing the strings to be very easy to reach.

While I have illustrated and described the 35 best means now known to me for carrying out my invention, I wish it to be understood that I do not restrict myself to the exact details of construction shown and described, but hold that any slight changes or variations as would 40 suggest themselves to the ordinary mechanic would clearly fall within the limit and scope of my invention.

Having now fully shown and described my 45 invention and the best means for its construction and arrangement to me known at this time, what I claim, and desire to secure by Letters Patent of the United States, is—

1. In a harp having the usual body and neck and hollow column and head, a recess formed 50 in the under side of the neck and communicating with the interior of the head, a plate secured to the neck on each side of said recess, a plurality of spindles pivoted between and by said plates, an arm extending up from each of 55 said spindles between said plates, a shaft secured between said plates within said head, a plurality of bell-crank pivoted on said shaft, a connecting-rod pivoted to each of said bell-crank and to each of said arms of said spindles, an adjustable arm attached to each of 60 said spindles outside of and adjoining one of said plates, a coil-spring surrounding said spindles, a plurality of adjustable plates secured on the side of the neck, an inner disk 65 and an outer disk pivoted over said adjustable

plates by a central screw, means for adjustably securing said outer disk to the inner disk circumferentially, a pair of fingers extending out from the face of the outer disks, an arm extending out from the inner disk, a connecting-bar pivoted at one end to said arm of the inner disk and pivoted at the other end to said adjustable arm, a rod pivoted to each of said bell-crank and extending down through said column, all substantially as shown and described and for the purposes set forth. 75

2. In a harp having the usual body, neck, head and hollow column, a recess formed in the under side of the neck adjacent to and in communication with the interior of the head, 80 a plate secured to the neck on each side of said recess, a plurality of spindles pivoted to and between said plates, an arm extending up from each of said spindles between said plates, a shaft secured between said plates within the 85 head, a plurality of bell-crank pivoted on said shaft, a connecting-rod pivoted to each of said bell-crank and to each of said arms, an adjustable arm attached to each of said spindles outside of said recess and adjoining 90 one of said plates, a spring surrounding each of said spindles, a plurality of adjustable plates secured on the side of the neck, an inner and an outer disk pivoted over said adjustable plates, means for adjustably securing 95 said outer disk to the said inner disk, a pair of fingers extending out from the face of the outer disk, an arm extending out from the inner disk, a connecting-rod pivoted at one end to said arm of the inner disk and pivoted 100 at the other end to said adjustable arm, a plurality of strings suspended vertically between said body and neck and tuned eleven strings to the octave, a bass octave and a plurality of 105 treble octaves, certain of said strings being disposed over said outer disks whereby they are adapted to be engaged by said fingers, all substantially as described.

3. In a harp having the usual body, neck and head, a hollow column vertically connecting the body and neck with the interposed head, a plurality of strings suspended between said body and neck and tuned eleven strings to the octave, a bass octave having an F, G, 110 A, B-flat, B, C, C-sharp, D, E, F and F-sharp 115 string with means for sharping the first, second and eighth of said strings, one or more treble octaves having a G, A, B-flat, B, C, C-sharp, D, E, F, F-sharp, and a G string with means for sharping the first and seventh 120 of said strings, the said means for sharping certain of said strings consisting of the following instrumentalities: a recess formed in the under side of the neck adjacent to and in communication with the interior of the head, 125 a plate secured to the neck on each side of said recess, a plurality of spindles pivoted by and between said plates, an arm extending up from each of said spindles between said plates, a shaft secured between said plates within the 130

head, a plurality of bell-crank pivoted on said shaft, a connecting-rod pivoted to each of said bell-cranks and to each of said arms, an adjustable arm attached to each of said 5 spindles outside of said recess and adjoining one of said plates, a plurality of adjustable plates secured on the side of the neck, an inner and an outer disk pivoted over said adjustable plates, means for rotatably securing 10 said outer disk to the inner disk, a pair of fingers extending out from the face of the outer disk, an arm extending out from the inner

disk, a connecting-bar pivoted at one end to said arm of the inner disk and pivoted at the other end to said adjustable arm, and means 15 for preventing rattling of the parts, all substantially as shown and described.

In testimony whereof I have hereunto signed my name to this specification in the presence of two subscribing witnesses.

THOMAS J. HISSEM.
